UNITED STATES PATENT OFFICE.

WILLIAM FISHER, OF BRADFORD, ENGLAND.

MECHANICAL MOVEMENT.

1,279,529.

Specification of Letters Patent. Patented Sept. 24, 1918.

Application filed September 21, 1915. Serial No. 51,771.

To all whom it may concern:

Be it known that I, WILLIAM FISHER, a subject of the King of Great Britain, residing at Bradford, England, have invented 5 new and useful Improvements in Mechanical Movements, of which the following is a specification.

This invention relates to improvements in or a modification of the dabbing brush mechanism described in the specification of 10 British Letters Patent No. 17,551 of 1913 granted to me in which the crank shaft is supported in ball or roller bearings in a boss in the supporting casting and a pin on said 15 crank is connected by a ball or roller bearing to one end of a link or connecting rod and a vertically movable dabbing brush slide having a stud or pin is connected by a ball or roller bearing to the opposite end of the 20 said link or connecting rod, and has for its object to eliminate the side pressure between the dabbing brush slide and its guides.

In the accompanying drawings:—

Figure 1 represents a side elevation, Fig. 25 2 a plan view and Fig. 3 a front elevation of one construction of dabbing brush mechanism according to this invention in which the crank shaft is situated above the connection between the connecting rod and the dabbing 30 brush slide.

Fig. 4 is a vertical section on the broken line *a*. *b*, Fig. 3.

Fig. 5 represents a sectional side elevation, Fig. 6 a plan view and Fig. 7 a front elevation of a modification in which the crank shaft is situated below the connection between the connecting rod and the dabbing brush slide.

Referring to the drawings, *a* is a suitable 40 bracket secured to the usual upright pillar or standard *b* of the combing machine. To the upper portion *c*, Figs. 1, 2 and 3, or the lower portion *c*, Figs. 5, 6, and 7, of the bracket *a* is secured a boss or bearing *d* in 45 which are inserted, near each end thereof, cages or the like 2 and 3 each containing a series of balls or rollers, which are adapted to form the bearing for a crank shaft 4. One end of said shaft is provided with the usual 50 pulley 5 which is so constructed as to project over and envelop the said boss *d*. The

opposite end of the shaft 4 is provided with a crank 4¹. The crank 4¹ has a pin 4^a to which is connected one end of a rod 6 whose opposite end is forked and is connected to a 55 stud 7 in the dabbing brush slide 8 movable vertically between guide strips on the bracket *a* and a retaining plate or cover *a*².

The crank pin 4^a is provided with a roller bearing 9 and the stud 7 with a roller bearing 12. The crank pin 4^a may have a ball or other suitable bearing or the stud 7 may have a ball bearing or both may have ball 60 bearings.

The said bearing 12 in the dabbing brush 65 slide 8 is situated in the same vertical plane as the bearing 9 on the crank pin 4^a so that the connecting rod 6 is straight and not bent as shown in the drawings of above cited specification. By this construction and arrangement of parts the side pressure between 70 the brush slide and its guides is eliminated and also the side pressure of the bearings at the ends of the connecting rod 6.

Claims:—

1. In a comb dabbing mechanism, a brush slide, a guide for the said slide, a crank, and a connecting rod pivotally connected with the said crank by a bearing and having a slotted fork straddling the said slide and 80 adjustable longitudinally thereof and pivoted to the latter by a bearing which is disposed so that a transverse plane passing medially therethrough is coincident with the corresponding plane of the said crank bearing. 85

2. In a comb dabbing mechanism, a brush slide, a guide for said slide, a crank, a connecting rod pivotally connected with said crank by a bearing and having a slotted fork straddling the said slide, a stud adjustably secured in said slots, a bearing fixed to said stud between the arms of said fork, and a collar formed on one end of said brush slide and surrounding said bearing. 90

In testimony whereof I have signed my name to this specification in the presence of two subscribing witnesses.

WILLIAM FISHER.

Witnesses:

A. S. HYDE,
CECIL A. S. BAXTER.
